(57) **CLAIM**

The ornamental design for a fishing rod holder, as shown and described.

DESCRIPTION

FIG. 1 is a perspective view of a fishing rod holder, showing our new design, wherein a receiving base therefor is shown in broken lines and forms no part;

FIG. 2 is an enlarged front elevational view;

FIG. 3 is a left-hand side elevational view;

FIG. 4 is a right-hand side elevational view;

FIG. 5 is an enlarged rear elevational view;

FIG. 6 is a top plan view; and,

FIG. 7 is a bottom plan view thereof.
